DRILL STEEL CENTRALIZER

Donald F. Samhammer, Utica, N. Y., assignor to Chicago Pneumatic Tool Company, New York, N. Y., a corporation of New Jersey

Application July 7, 1954, Serial No. 441,728

12 Claims. (Cl. 255—51)

This invention relates to rock drills and more particularly improvements in a centralizer, or guide, for a drill steel as used in a rock drill of the drifter type.

In rock drilling operations utilizing drills of the drifter type, guide means are often provided to prevent the drill steel from "crawling" when starting a hole on an irregular work surface. Such guide means are of various types, including arrangements wherein a pair of pivoted arms is adapted to guidingly grasp the drill steel, and arrangements wherein a guide arm is adapted to swing in an arc parallel to the movement of the drill steel, and which includes a drill steel lock in the form of a latch element. The device of the present invention is of the latter type and distinguishes over known devices of the prior art by providing for automatic operation of the latch element by direct engagement with the drill steel during movement of the guide arm, which results in an arrangement of extreme simplicity and one which assures positive locking action. The device of the invention also includes a power operated guide arm actuator, which provides for remote control of the guide arm if desired.

An object of the invention is to provide a drill steel centralizer which will prevent a drill steel from "crawling" when starting a hole in an irregular work surface.

A further object of the invention is to provide a drill steel centralizer with an improved latch element arrangement which is operated by direct engagement with the drill steel, to either lock or unlock the drill steel from guided condition.

Further objects are to provide a drill steel centralizer which is extremely simple in structure, of rugged construction, efficient and reliable in operation, and which may be remotely controlled.

These and further objects and features of the invention will become more apparent from the following description taken in consideration with the accompanying drawings in which:

Fig. 1 is a side elevational view, partly in section and broken away in part, of a drill steel centralizer embodying the invention;

Fig. 2 is an end view of the drill steel centralizer of Fig. 1;

Fig. 3 is a top view of a portion of the drill steel centralizer;

Fig. 4 is an end view, partly in section, of a portion of the drill steel centralized as seen from line 4—4 in Fig. 3;

Fig. 5 is a plan view of a latch element used in the device of Fig. 1;

Fig. 6 is an end view in section as seen from line 6—6 in Fig. 5;

Fig. 7 is a perspective view of a latch spring used in the device of Fig. 1; and

Fig. 8 is a sectional view of a portion of the drill steel centralizer as seen from line 8—8 in Fig. 2.

Referring now to the drawings, and more particularly to Fig. 1 thereof, numeral 11 indicates the front end of a rock drill of the drifter type, which is supported for longitudinal movement upon a frame, or guide shell 12 in the manner well known to those skilled in the art. Affixed to the forward portion of the guide shell 12, is a drill steel centralizer arrangement embodying the features of the invention, which arrangement comprises two operative

2

parts viz, a guide arm assembly 13, and a guide arm actuator assembly 14.

The guide arm assembly 13, includes a guide arm 16 which has a pair of ears 17 at the lower end, a head portion 18 at the upper end having a drill steel slot 19, and a lock, or latch element 21 pivotally affixed to the head portion for movement into position above the slot 19. The ears 17 are arranged for connection to a pin 22 which is supported for rotary movement in a bracket 23, which is attached to the forward end of the guide shell 12 in a manner as to maintain the axis of pin 22 at right angles to the path of movement of the rock drill. The drill steel slot 19 is positioned so as to receive a drill steel 24 of the rock drill when the guide arm is in vertical position, whereby the drill steel will be held in guided condition. The latch element 21 is positioned at an angle of approximately 15° relative a plane perpendicular to the axis of the guide arm as best seen in Fig. 2. A bolt 26 having a nut 27, is arranged to pivotally secure the latch element in position upon the guide arm. The end of latch element 21 has an end recess 28 which allows for engagement of the end of the latch element with a hook, or lip portion 29 formed integrally on the head portion 18, whereby the latch element is better maintained to resist upward impact of the drill steel during operation. A top edge of the latch element has a 45° chamfer 31 extending from the recess 28, while the opposite lower edge of the latch element has a 45° chamfer 32. The purpose of chamfers 31 and 32, is to provide better camming action to the latch element when it engages the drill steel 24, so as to rotate the latch element out of locking position; the chamfer 31 is effective when the drill arm is being raised to vertical or operative position, while the chamfer 32 is effective when the drill arm is being lowered to horizontal, or non-operative position.

A spring 33 surrounding the bolt 26, is located beneath the latch element, and has arms, or ends 34 and 36 which are formed to engage the latch element on each side. Vertical slots 37 and 38 are formed in the latch element to

receive the ends 34 and 36 respectively of the spring 33, the extremities of said spring entering a hole 40 formed in the latch element. The width of slots 37 and 38 as well as the diameter of hole 40 is greater than that of the spring ends so that one of said spring ends can cock in the respective slot and hole when the latch is rotated, thereby preventing undue distortion on the spring arm under action. The spring ends 34 and 36 are arranged on each side of a portion 39 formed on the head portion 18, so as to fix the spring against rotary movement, and to provide spring resistance to the latch element in either direction

45 of rotation. A pin 41 is affixed in the guide arm to project into a groove formed on bolt 26, to prevent the latter from rotating. Formed integral with the head portion 18 are drill steel guide means in the form of two fingers 43

50 which are flared in a rearward direction, said fingers being effective to guide the drill steel 24 into the drill steel slot 19 when the guide arm is being swung to vertical, or holding position.

The guide arm 16 has a bore 44 for reception of a guide arm positioning means including a spring 46 compressively 60 engaging a wedge type plunger 47, which is adapted to enter one of two slots 48, 49 formed in the bracket 23. The purpose of the guide arm positioning means is to maintain the guide arm in either vertical or horizontal position, as will be easily understood. The plunger 47 has a flat portion 51 on the side thereof, for engagement by a pin 52 affixed in the guide arm 16, whereby the plunger 47 is maintained in guided condition for proper engagement with slots 48, 49.

70 The operation of the above described guide arm arrangement is believed to be quite apparent, and briefly is

as follows: Assume that the guide arm assembly 13 is in horizontal, or non-operative position, and the drill steel 24 is in position in the drill 11, and drilling operation is about to commence, the tool operator need merely swing the guide arm assembly into vertical position, whereupon the latch element 21 will be automatically swung into drill steel holding position as shown in Figs. 1 and 2. In arriving at such position, the latch element will be forced from over the drill steel slot 19, by virtue of sliding engagement with the drill steel in the region of the chamfer 31. As soon as the drill steel is in position in slot 19, and the latch element is clear of the drill steel, the latch element will be swung into holding position by action of the spring 33. The drill steel 24 is thus held in guided position so that it will not crawl during start of a hole on an irregular work surface.

As the drill 11 approaches the end of travel upon the guide shell 12, it engages the fingers 43 of the guide arm 16, thus rotating the latter forwardly toward horizontal position. During such movement the latch element 21 will be forced from over the drill steel slot 19, by virtue of sliding engagement with the drill steel in the region of the chamfer 32. As soon as the latch element is forced out of contact with the drill steel, the latch element will be swung back into position over the now empty drill steel slot 19, by action of the spring 33.

The guide arm actuator assembly 14, which is adapted to provide power operation of the guide arm assembly 13 by remote control, includes a cylinder 53, front and rear end cylinder heads 54, 56 respectively, and a piston 57 having a piston rod 58 extending through and supported by the front end cylinder head 54. Two bolts 59 extend through flanges formed on cylinder heads 54 and 56 to maintain the latter in position on the cylinder 53. The front cylinder head 54, has a passageway 61 opening unto the inside face, which passageway extends into a bore 62 threaded to receive a pipe fitting 65. The rear cylinder head 56 has a centrally disposed hole 63 which is threaded to receive a pipe fitting 70. It will be seen that application of pressurized fluid via passageway 61 will force the piston 57 rearwardly in the cylinder, assuming of course that the hole 63 is open to exhaust, and that application of pressurized fluid via hole 63 will force the piston 57 forwardly in the cylinder, assuming that passageway 61 is open to exhaust.

The front cylinder head 54 has a horizontally disposed flange 64 (Fig. 2) which is affixed to the underside of guide shell 12, by bolt means 66, and which supports the actuator assembly 14 in operative position.

The external end of the piston rod 58 has a pin 67 affixed thereto, which pin projects from each side of the piston rod to slidably engage slots 68 formed in a pair of crank arms 69 which extend from a hub portion 71 affixed to the pin 22. In such manner the reciprocal movement of piston 57 is arranged to provide rotary motion of the guide arm assembly 13, so that the latter may be raised or lowered in accordance with requirements. It is pointed out that the guide arm assembly 13 may be used manually, and with or without association with an actuator assembly of the type described.

What is claimed is:

1. In a rock drill mounted for movement in a drill shell, a drill steel centralizer having a guide arm which is pivotally affixed to the front end of the drill shell and is adapted to swing in a plane coincident with the path of movement of the drill, said guide arm having a head portion including a drill steel slot which in one position of the guide arm is adapted to supportingly engage a drill steel operatively positioned in the rock drill, a latch element rotatably mounted upon the head portion and arranged to extend over the drill steel slot and movable by sliding engagement with the drill steel, and resilient means adapted to urge the latch element into position over the drill steel slot.

2. In a rock drill mounted for movement in a drill shell,

a drill steel centralizer having a guide arm which is pivotally affixed to the front end of the drill shell and is adapted to swing in a plane coincident with the path of movement of the drill, said guide arm having a head portion including a drill steel slot which in one position of the guide arm is adapted to supportingly engage a drill steel operatively positioned in the rock drill, a latch element rotatably mounted upon the head portion and arranged to extend over the drill steel slot and movable by sliding engagement with the drill steel, a spring means adapted to urge the latch element into position over the drill steel slot, and drill steel guide fingers formed on the head portion and adapted to guide the drill steel into the drill steel slot.

15. In a rock drill having a drill steel centralizer according to claim 2, wherein a lip portion is arranged on the head portion to project over the drill steel slot to engage the upper surface of the latch element when it is in position over the drill steel slot.

20. In a rock drill having a drill steel centralizer according to claim 3, wherein said latch element is disposed to rotate in a plane forming an angle of approximately 15° with respect to the axis of the guide arm.

25. In a rock drill having a drill steel centralizer according to claim 4, wherein a guide arm positioning means is arranged to maintain the guide arm in either a vertical or horizontal position, said guide arm positioning means including a plunger disposed within the guide arm which is spring biased for engagement with slots formed in a bracket affixed to the drill guide shell.

30. In a rock drill having a drill steel centralizer according to claim 1, a guide arm actuator assembly affixed to the drill shell and adapted to provide rotary movement of said guide arm about its pivot.

35. In a rock drill having a drill steel centralizer according to claim 6, said guide arm actuator including a cylinder, a piston slidably maintained within the cylinder, front and rear cylinder heads positionally maintained upon the cylinder, a piston rod connected to the piston and supported for sliding movement within the front head and extending exteriorly thereof, and a crank arm arranged between the piston rod and the guide arm.

40. In a rock drill having a drill steel centralizer according to claim 7, pressure fluid connections in the front and rear cylinder heads adapted for alternative delivery of pressure fluid to opposite sides of the piston to cause reciprocable movement of the piston within the cylinder.

45. In a rock drill having a drill steel centralizer according to claim 8, wherein drill steel guide fingers are formed on the head portion and which are adapted to guide the drill steel into the drill steel slot.

50. In a rock drill having a drill steel centralizer according to claim 9, wherein a lip portion is arranged on the head portion to project over the drill steel slot to engage the upper surface of the latch element when it is in position over the drill steel slot.

55. In a rock drill having a drill steel centralizer according to claim 10, wherein said latch element is disposed to rotate in a plane forming an angle of approximately 15° with respect to the axis of the guide arm.

60. In a rock drill having a drill steel centralizer according to claim 11, wherein a guide arm positioning means is arranged to maintain the guide arm in either a vertical or horizontal position, said guide arm positioning means including a plunger disposed within the guide arm which is spring biased for engagement with slots formed in a bracket affixed to the drill steel shell.
